DESIGN FOR A COOKY JAR

Samuel W. Rapp, Morton, Ill.

Application May 26, 1948, Serial No. 146,624

Term of patent 7 years

(Cl. D58—25)

To all whom it may concern:

Be it known that I, Samuel W. Rapp, a citizen of the United States, residing at Morton, in the county of Tazewell and State of Illinois, have invented a new, original, and ornamental Design for a Cooky Jar, of which the following is a specification, reference being had to the accompanying drawing, forming part thereof.

In the drawing:

Fig. 1 is a side elevation of my design for a cooky jar.

Fig. 2 is a plan of said cooky jar.

I claim:

The ornamental design for a cooky jar as shown.

SAMUEL W. RAPP.
